US0D1012983S

(12) **United States Design Patent** (10) Patent No.: **US D1,012,983 S**
Gallagher (45) Date of Patent: ** Jan. 30, 2024

(54) **BENCH DRILLING MACHINE**

- (71) Applicant: **Scheppach GmbH**, Ichenhausen (DE)
(72) Inventor: **Philip Gallagher**, Ichenhausen (DE)
(73) Assignee: **Scheppach GmbH**, Ichenhausen (DE)
(**) Term: **15 Years**
(21) Appl. No.: **29/847,485**
(22) Filed: **Jul. 25, 2022**

Related U.S. Application Data

- (63) Continuation of application No. 35/511,422, filed on Jan. 22, 2021 (U.S. filing date under 35 U.S.C. 384), and having an international filing date of Jan. 22, 2021, now Pat. No. Des. 970,562.
